DESIGN FOR A COMBINED INK LINE REEL AND INKING DEVICE

Procoro Bastero, Iloilo City, P. I.

Application April 6, 1939, Serial No. 84,101

Term of patent 7 years

To all whom it may concern:

Be it known that I, Procoro Bastero, a citizen of the United States of America, residing at Iloilo City, Philippine Islands, have invented a new, original, and ornamental Design for a Combined Ink Line Reel and Inking Device, of which the following is a specification, reference being had to the accompanying drawing, forming part thereof wherein:

Figure 1 is a view in side elevation of a combined ink line reel and inking device, showing my new design.

Figure 2 is a top plan view.

Figure 3 is a front elevation.

The portions shown in dotted lines in Figures 1 and 2 have been omitted from Figure 3 for convenience of illustration.

I claim:

The ornamental design for a combined ink line reel and inking device, as shown and described.

PROCORO BASTERO.
